UNITED STATES PATENT OFFICE.

ALONZO FOWLER KEMPTON, OF WAWANESA, MANITOBA, CANADA.

BELT HANGER.

1,410,925.

Specification of Letters Patent. Patented Mar. 28, 1922.

Application filed May 16, 1921. Serial No. 470,158.

To all whom it may concern:

Be it known that I, ALONZO FOWLER KEMPTON, a subject of the King of Great Britain, residing at the village of Wawanesa, in the Province of Manitoba and Dominion of Canada, insurance manager, have invented certain new and useful Improvements in Belt Hangers, of which the following is a specification.

10 This invention relates to improvements in belt hanger, and the objects of the invention are to provide a simple and effective device for holding men's and other belts in such a way that they may be supported and displayed in minimum space and to maximum advantage.

Further objects of the invention are to construct a device at low cost of readily available material and generally to adapt 20 it to perform the functions required of it. It consists essentially of the improved construction hereinafter described in detail in the accompanying specification and drawings.

25 In the drawings:—

Figure 1 is a perspective view of the invention.

Figure 2 is an elevation thereof.

Figure 3 is a section on the line 3—3, Figure 2.

In the drawings, like characters of reference indicate corresponding parts in all the figures.

A indicates a supporting member of flexible material such as leather and which as

shown is substantially bell shape, having an eyelet 10 at the upper end by which it may be suspended and being formed with a plurality of slots 11 through which the belts to be supported may be inserted. I 40 have shown two rows of three slots, each slot being formed with a lower edge 12 at substantially right angles to the surface of the flexible member A. It will be seen that when the belts are inserted through the slot, 45 they will be held in spaced relation.

As many changes could be made in the above construction and many widely different embodiments of my invention within the scope of the claim, constructed without departing from the spirit or scope thereof, it is intended that all matter contained in the accompanying specification and drawings shall be interpreted as illustrative and not in a limiting sense. 50

What I claim as my invention is:—

A belt hanger comprising a flexible supporting member of bell shape, having an eyelet on the upper end, and being formed with a plurality of slots arranged in two 60 rows, each slot being formed with a lower edge at substantially right angles to the surface of the flexible member, and with an upper edge at an acute angle thereto.

In witness whereof I have hereunto set 65 my hand in the presence of two witnesses.

ALONZO FOWLER KEMPTON.

Witnesses:

CHARLES LORRAINE ATKINSON.

EDWARD LOUIS McDONALD.
